UNITED STATES PATENT OFFICE.

THEODORE D. PICKELL, OF NEW YORK, N. Y., ASSIGNOR TO A. V. VICTORIUS & COMPANY,
OF NEW YORK, N. Y., A CORPORATION OF NEW YORK.

CLEANING ATTACHMENT FOR CIRCULAR-KNITTING MACHINES.

Application filed August 10, 1926. Serial No. 128,355.

My invention relates to an improvement in knitting machines and more particularly to knitting machines of the circular type.

Knitting machines of the type to which my invention relates are, as is well known, utilized for the knitting of hosiery, in the knitting of which the machine is given a rotary motion, during which all the needles are down and in action, for the production of the leg, and a reciprocatory motion, during which a part of the needles are lifted and held out of action, for the production of the heel and toe.

The machines operating at relatively high speed require a substantial amount of lubrication as a result of which, in the course of time, an accumulation of oil, fine metal chips and dust occurs in the needle cylinder and on the needles carried thereby. During the rotary motion of the machine, all the needles are operated, being lifted to a given height by the knitting cams, and the oil, dust, etc. does not have an opportunity to accumulate on the upper portion of the needles due to the constant wiping thereof by the loops of yarn in the formation of the stitches. The oil, dust, etc., however, accumulates on the needles and in the needle cylinder below the portion of the needles wiped by the yarn during rotary motion of the machine.

When the machine is shifted to reciprocating motion, as has been indicated, part of the needles are thrown out of action which is accomplished by raising or lifting the needles substantially higher than the needles in action are raised or lifted by the knitting cam and maintaining them in raised position. The needles thrown out of action carry loops of yarn which, since the needles are raised higher than in knitting, are drawn down over a part of the needles upon which oil, dust, etc. has accumulated and the yarn becomes dirty, resulting in the knitting into the stocking of a quantity of oil, dust, metal, etc. when the needles are again thrown into action, which cannot be washed out effectively and which causes the appearance of a dark streak when the hosiery is dyed in any relatively light color.

When a machine becomes dirty it has heretofore been necessary to take it apart and thoroughly wash the needle cylinder and needles, since while the yarn on the needles thrown out of action picks up the dirt from the needles, the needles when thrown back

into action pick up dirt from the needle cylinder which is transferred to the yarn upon them when they are next thrown out of action and so on indefinitely unless the machine is cleaned.

The operation of cleaning a machine, requiring as it has the removal of the needles and needle cylinder, is an uneconomic proceeding since it requires some skill and substantial time during which the machine is necessarily out of operation.

Now it is the object of my invention to provide means whereby the needles and needle cylinder may be readily cleaned, without the necessity for removal, in a simple manner and in a minimum of time.

Having now indicated, in a general way, the nature and purpose of my invention, I will proceed to a description of a preferred embodiment thereof with reference to the accompanying drawings in which:—

Fig. 1 is a developed view of the cams for acting on the needles of a circular knitting machine, showing an embodiment of my invention.

Fig. 2 is a detail view, partly in section, of a part of a circular knitting machine embodying my invention.

In the drawings *a* indicates the base of a knitting machine, *b* a needle cylinder, *c* a gear carried by the cylinder and *d* a cam ring. The needles *e* arranged about the needle cylinder are provided as is usual, some with long butts *f* and some with short butts *g*, upon all of which the knitting cams *h* operate. Picker cams *i* are provided for lifting and throwing out of action the needles having long butts *f* and picker cams *j* are provided for lowering and throwing the needles back into action. The line *x* indicates the inactive position of the long butt needles or the height to which the needles thrown out of action are raised.

At a suitable point on the cam ring there is supported a bracket *k*, which serves to support a cam *n* and a lowering cam *o*. The bracket *k* is preferably adjustably secured to the cam ring as by a bolt *l*, threaded into cam ring and passing through a slot *m* in the bracket, to enable adjustment of the cam into and out of the path of the needle butts. The cam *n* is so proportioned as to engage the butts of all the needles and raise or lift them to a height somewhat greater than the height to which the long butt needles are

lifted by the picker cams *i*. The needles respectively after passing the cam *n* are returned to normal by cam *o*.

Thus it will be noted that when the cam *n* is positioned to operate on the needles, all the needles as they pass the cam respectively will be lifted to a height greater than that to which the long butt needles are lifted when they are thrown out of action. If now the machine be operated with a rotary movement and a soft absorbent yarn be fed to the needles, the yarn on the needles, as they are raised by the cam *n*, will wipe all the needles down below the point to which the yarn is drawn on the long butt needles when they are thrown out of action in the reciprocatory movement of the machine. The needles as they are wiped will lower and wipe the needle cylinder, being again wiped themselves when they are again acted on by cam *n*, so that if the machine be operated for a relatively short time on rotary movement, with the cam *n* operative, the needle cylinder and needles will be thoroughly cleaned, thus avoiding the necessity for disassembling the machine.

It will be understood that I do not intend my invention to be limited to its adaption to any particular type of circular knitting machine nor to any particular form of cam or method of attachment, since it may be adapted to various types of circular machines and may take a variety of forms.

It will also be understood that if desired several cams similar to cam *n* may be positioned to act on the needles with the result that the needles will be lifted several times in each revolution of the machine, instead of but once as in the embodiment described and the machine may thus be cleaned more quickly.

Having now fully described my invention, what I claim and desire to protect by Letters Patent is:—

45 1. A cleaning attachment for circular knitting machines comprising, in combination, needles, knitting cams, picker cams

adapted to lift certain of the needles to an inactive position and means adapted to lift all of the needles to a height not less than that to which certain of the needles are adapted to be lifted by the picker cams.

2. A cleaning attachment for circular knitting machines comprising, in combination, a needle cylinder, needles, knitting cams, means to rotate said cylinder, means to reciprocate said cylinder, picker cams adapted to lift certain of the needles to an inactive position when said cylinder is reciprocated and a cam adapted to be positioned to lift all of said needles when said cylinder is rotated to a height not less than that to which certain of the needles are adapted to be lifted by the picker cams.

3. A cleaning attachment for circular knitting machines comprising, in combination, a needle cylinder, needles, knitting cams, means to rotate said cylinder, means to reciprocate said cylinder, picker cams adapted to lift certain of the needles to an inactive position when said cylinder is reciprocated, a cam adapted to be positioned to lift all of said needles when said cylinder is rotated to a height not less than that to which certain of the needles are adapted to be lifted by the picker cams and a cam adapted to be positioned to return the needles to normal.

4. A cleaning attachment for circular knitting machines comprising, in combination, a needle cylinder, needles, knitting cams, means to rotate said cylinder, means to reciprocate said cylinder, picker cams adapted to lift certain of the needles to an inactive position when said cylinder is reciprocated, a cam adapted to be positioned to lift all of said needles successively when said cylinder is rotated to a height not less than that to which certain of the needles are adapted to be lifted by the picker cams.

In testimony of which invention, I have hereunto set my hand, at Shelby, N. C., on this 27th day of July, 1926.

THETUS D. PICKELL.
